STORAGE VAULT CONDITIONING UNIT

Walter G. Haertel, David H. Oliver, and Verner H. Smallbeck, Minneapolis, Minn., assignors to Walter Haertel Company, Minneapolis, Minn., a corporation of Minnesota

Application June 10, 1949, Serial No. 98,284

5 Claims. (Cl. 62—6)

1

This invention relates to conditioning units particularly adapted for such rooms as fur storage vaults, but also adaptable for use in other rooms and chambers.

To care for furs when not in use the furs are hung in storage vaults. In these vaults for the proper preservation of the furs the air should be maintained at a uniform rather low temperature and the air should be maintained also in a rather dry condition. At times it is desirable to fumigate the vault, and after fumigation it is necessary to ventilate the vault to eliminate the fumigant.

It is one of the objects of this invention to provide a conditioning unit for such rooms as fur storage vaults and the like which can be employed for refrigerating, dehumidifying, fumigating and ventilating such rooms.

Another object is to provide such a unit which while circulating the air in the room will cool the air automatically to maintain the room at a desired relatively low temperature and which in case the relative humidity of the air becomes too high will dehumidify the air automatically.

A still further object is to provide such a unit which can be employed for refrigerating and dehumidifying the air in such a room as a fur storage vault and which at times can be operated to circulate and disseminate a fumigant in the room and can thereafter be operated to ventilate the room to eliminate the fumigant therefrom, whereupon the unit can be again used for refrigerating and dehumidifying the air in the room.

A further object is to provide a compact unit which will occupy but small space in the fur storage vault or other room in which it is used and which is of relatively simple and inexpensive construction and is highly efficient in use.

The objects and advantages of the invention will more fully appear from the following description made in connection with the accompanying drawings wherein like reference characters refer to the same or similar parts throughout the different views, and in which

Fig. 1 is a perspective view of a portion of a fur storage vault wherein one of the conditioning units of the present invention is installed;

Fig. 2 is a view in front elevation of the conditioning unit, portions of the front paneling being broken away to more clearly illustrate the internal structure of the device;

Fig. 3 is a view looking toward the right side of the conditioning unit as shown at the left of Fig. 1, certain of the parts being broken away and other parts being shown in vertical section;

Fig. 4 is a view looking toward the left side of

2

the device shown at the right of Fig. 1, a portion of the paneling being broken away;

Fig. 5 is a perspective view showing the linkage system between the louver operating motor and the louvers operated thereby;

Fig. 6 is a perspective view showing the linkage system between the damper operating motor and the two dampers operated thereby;

Figs. 7, 8, 9, and 10 are diagrammatic views illustrating the conditioning unit as employed respectively for refrigerating, dehumidifying, fumigating, and ventilating, the direction of air circulating being shown by arrows, and the movable parts and certain other parts being shown in the condition they will be in as the unit is used for the different purposes;

Fig. 11 is a diagrammatic view illustrating the principal parts of the refrigeration unit employed, the electrical circuit to the motor operating this refrigerating unit being also shown; and

Fig. 12 is a wiring diagram for the conditioning unit showing wiring other than to the refrigeration unit motor.

Referring first to Figs. 1 to 6 inclusive, there is there illustrated an air conditioning unit for fur storage vaults exemplifying the invention. This unit includes a skeleton frame 13 of rectangular shape in transverse and longitudinal section supporting a base 14, a shelf or dividing partition 15 about midway of the height of the frame, lower enclosure straps 16 just above the level of the shelf 15 and upper enclosure straps 17 spaced downwardly from the top of the skeleton frame. The front of the frame 13 is closed by an upper fixed front panel 18, midway lateral front panels 19, and upper and lower removable front panels 20 and 21 having lower edges which will interlock with portions of the frame, and handle latches 22 which will interlock with the panels 18 and 19 respectively. The right side of the skeleton frame 13 is closed by a right side panel 23, while similarly the left side of the skeleton frame is closed by a left side panel 24. The back of the frame is closed by a back panel 25 and the top is closed by a top panel 26.

The shelf or partition 15 divides the casing into an upper plenum chamber A and a lower refrigeration unit chamber B within which all parts of a refrigeration unit C, except the expansion coil of the unit, are mounted to be supported by base 14. This refrigerating unit may be of any standard type and it is thus unnecessary to describe the same in detail.

An air intake opening 27 is formed in the front paneling of the unit leading into the plenum

chamber A. This opening is located between the two removable front panels 20 and 21 and between the two lateral front panels 19. Mounted on the shelf 15 immediately behind this inlet opening 27 is an expansion coil 28 for the refrigeration unit, this coil being supplied with liquid refrigerant by a pipe 29 leading from the refrigeration unit and a pipe 30 being connected to the upper portion of the expansion coil for carrying off the refrigerant in gaseous form and conveying it back to the refrigeration unit C. It should perhaps be stated that the expansion coil 28 is a finned coil very similar to a tubular finned radiator.

Mounted at the rear of the expansion coil 28 at the two end portions thereof are a pair of up-standing bars 31 forming a louver frame within which outwardly projecting horizontal pivot pins 32 carried by louvers 33 are journaled. These louvers accordingly are mounted for swinging movement about horizontal axes and all the louvers are connected for swinging movement together by arms 34 fixed to the pins 32 at corresponding ends of the louvers and by a link 35 pivotally connected to the inner ends of these arms 34. The pin 32a at one end of the uppermost louver 33 has secured thereto an operating lever 36 and it will be seen that by swinging this lever all of the louvers 33 can be swung so as to open them to a greater or lesser extent, thereby regulating the amount of air that can pass through the inlet 27 and through the expansion coil 28. For the purpose of swinging the louvers from a full open substantially horizontal position to a partially closed position inclining inwardly and downwardly from their outer edges there is provided a stalled torque motor 37, and this motor may be secured at a convenient point to the skeleton frame 13. The motor 37 has a motor shaft 38 to which an arm 39 is connected, this arm 39 in turn being pivotally connected to one end of a link 40, the remaining end of which is pivotally connected to the lever 36. The said motor 37 when energized will act to partially close the louvers 33 to carry them to the inclined position referred to and will then stall to hold the louvers in the partially closed position. The pin 32a of the uppermost louver carries near its outer end an arm 41 from which is suspended a weight 42, and this weight will act to open the louvers 33 and thereafter hold the louvers in open position upon de-energization of the stalled torque motor 37.

Below the expansion coil 28 there is located a drip pan 43 for the collection of any water dripping off the expansion coil and a pipe 44 receives from this drip pan and may be carried off to a point to drain into a suitable receptacle or into a sewer.

There are provided through the top panel 26 twin discharge outlet openings communicating with the plenum chamber A and one of these outlets will be called the room outlet 45, while the other outlet will be designated the outside outlet 46. Supported within the upper portion of the plenum chamber A as upon cross bars 47 carried by the upper straps 17 is a blower 48 which may be of the squirrel cage type having inlet openings 48a at the two ends of its casing receiving from the plenum chamber A. The shaft of this blower is designated by the numeral 48b. A twin branch outlet housing 49 is connected to the outlet mouth of the blower 48 and one branch 49a of this housing projects through the room discharge outlet 45 to discharge into the

vault or room within which the unit is placed, while the other branch 49b projects through the outside discharge outlet 46 and is connected to a conduit 50 which will be carried to a point outside the room or vault within which the conditioning unit is located to discharge as to the outside air. A motor bracket 51 is connected by a pivot 52 to the housing of the blower 48 and a blower motor 53 is carried by this bracket 51. The lower end of the bracket 51 carries a set screw 54 which will be carried by the weight of the motor into engagement with a portion of the housing of the blower and by adjusting the screw 54 the shaft 53a of the motor can be spaced a greater or a lesser distance from the blower shaft 48b. The motor shaft 53a carries a pulley 55 and a belt 56 runs over this pulley and over another pulley 57 carried by the blower shaft 48b at one end thereof, the screw 54 acting to adjust the tension of this belt.

Mounted at the central portion of the twin housing 49 between the two branches 49a and 49b on a damper shaft 58 is a control damper 59 which will control the discharge from the blower 48 to alternatively direct this discharge through the branch 49a or the branch 49b of the housing 49, depending on the position to which the damper is swung. The damper shaft 58 carries adjacent one end thereof an operating lever 60. For swinging the damper 59 there is provided a stalled torque motor 61 secured in a convenient position to the skeleton frame 13 of the unit, and this motor 61 has a motor shaft 62 to which an arm 63 is connected. A link 64 is pivotally connected at one end to the arm 63 and is pivotally connected at its other end to the lever 60. A tension spring 65 is connected at one end to the link 64 and is connected at its other end to a fixed portion of the frame 13, and this spring normally urges the linkage arrangement to such a position that the control damper 59 closes off the branch 49b passing through the outside outlet 46, thereby leaving the branch 49a running through the room outlet 45 open. When the motor 61 is energized, the parts will be actuated to swing the control damper 59 to a position wherein passage through the branch 59a is obstructed by the damper, leaving passage through the branch 49b open, thereby permitting the discharge of air from the blower through the outside outlet 46 and the conduit 50 to a point outside the room wherein the conditioning unit is located. After the control damper 59 has been swung to close the branch 49a the motor stalls, and while still energized it holds the damper in this position against the tension of the spring 65.

In the upper left portion of the plenum chamber A there is mounted a box-like housing 66 having a frame-like upper portion projecting through an opening 67 formed in the top panel 26. Another opening 68 in the right side panel 23 affords communication between the housing 66 and the room or vault within which the conditioning unit is located. The opening 68 is framed by a frame 69 carrying an air filter 70 for purifying the air passing therethrough. A conduit 71 is attached to the upwardly projecting portion of the housing 66 and this conduit runs outwardly to a point beyond the room or vault within which the unit is located and will be preferably extended to the outside air. The housing 66 forms in reality a portion of an air inlet conduit which at times may be employed for supplying fresh air to the room or vault to supplant air discharged through

the branch 49b and conduit 50. The opening 67 is controlled by a damper 72 secured to a damper shaft 73 journaled in the upper portion of the housing 66. This damper shaft 73 has secured thereto an operating lever 74, and a link 75 is pivotally connected at one end to the lever 74 and is pivotally connected at its other end to an arm 76 secured to the opposite end of the control damper shaft 58 from that to which the lever 56 is secured. The linkage is such between the control damper shaft 58 and the damper shaft 73 that the fresh air inlet damper 72 will be held in closed position relative to the inlet opening 66 when the control damper 59 is retained in position by the spring 65 to close off the outlet branch 49b in the blower housing 49. Accordingly, when the motor 61 is energized, the fresh air control damper 72 will be swung to an open position as the control damper 59 is swung to a position to close the branch 49a of the blower housing and open the branch 49b of the blower housing.

Mounted on the right side panel 23 of the unit is a control panel 77 carrying a humidostat 78, a thermostat 79 and a casing 80 within which a thermometer and humidity indicator are located. An electric switch 81 which may be called the main refrigeration control switch is also mounted on this control panel.

As diagrammatically illustrated in Fig. 11, the refrigeration unit C includes a motor 82 driving a compressor 83, the said compressor communicating with a conditioner receiver 84 wherein the compressed refrigerant is cooled to liquify the same. From the conditioning receiver the refrigerant runs to an expansion valve 85 and hence to the expansion coil 28 from whence the refrigerant in gaseous form is carried back to the compressor 83. Line wires 86 run to a suitable refrigeration unit motor switch 87 which may be located at any desired point either within the room or vault where the conditioning unit is located or outside the room or vault. From the switch 87 wires 88 run to a magnetic starter 89 and thence to the motor 82 of the refrigeration unit.

Referring now to the wiring diagram Fig. 12, there is there diagrammatically illustrated the fan motor 53, the stalled torque louver operating motor 37 and the stalled torque control valve motor 61. Also, the humidostat 78 and the thermostat 79 are shown as is the main refrigeration control switch 81. The switch 81 is a single throw, double contact switch and includes fixed contacts 81a and 81b and movable contact 81c and 81d adapted to respectively engage with the two fixed contacts 81a and 81b. There is also provided a double contact relay switch designated as an entirety by the numeral 90. This switch includes relay 90a, armature 90b, and movable contacts 90e and 90f carried by the armature 90b and adapted for cooperation respectively with fixed contacts 90c and 90d when the armature 90b is attracted by the energization of the relay 90a. There is also provided a fumigation switch 91 and a ventilation switch 92, both of which are preferably located at any convenient point outside the room or vault within which the conditioning unit is located so that they can be thrown without entering the vault or room. The fumigation switch includes a fixed contact 91a and a movable contact 91b, while the ventilation switch includes a fixed contact 92a and a movable contact 92b.

A pair of line wires running from any suitable source of electrical supply are designated by the

numerals 93 and 93a respectively. From the line wire 93 a conductor 94 runs to the fan motor 53 and another conductor 95 runs from the fan motor to the fixed contact 81a of the main refrigeration control switch 81. Another conductor 96 runs from the movable contact 81c of the switch 81 to the thermostat 79, and another conductor 97 runs from the thermostat 79 to the movable contact 81d of the switch 81. A conductor 98 runs from the fixed contact 81b of the switch 81 to the line wire 93a. From the conductor 94 a conductor 99 runs to the louver motor 37 and from this motor a conductor 100 runs to the fixed contact 90d of the relay switch 90. Another conductor 101 runs from the conductor 95 to the fixed contact 90c of the relay switch 90. A conductor 102 connects with both movable contacts 90e and 90f of the relay switch and runs over to tap the conductor 98. A conductor 102 taps the conductor 94 and runs over to the coil of the relay 90a and from the relay coil a conductor 103 runs to the humidostat 78. From the humidostat 78 a conductor 104 runs to the movable contact 81d of the main refrigeration switch 81. A conductor 106 taps the conductor 103 and runs to the fixed contact 91a of the fumigation switch. A conductor 107 is connected to the movable contact 91b of the fumigation switch and it is also connected to the movable contact 92b of the ventilating switch and this conductor 107 connects with the fixed contact 81b of the main refrigeration switch 81 to connect with conductor 93.

It should be stated that located within the plenum chamber A and resting on the shelf or partition 15 behind the louvers 31 is a tank 108 for containing a liquid fumigant of the vaporizing type. This tank has end walls which project up above the level of the tank and rods 109 extend across between the upper portions of these walls, and these rods in turn support hanger arms 110 from which wicks 111 are suspended, these wicks running into the tank 108 and acting to draw liquid from the tank by capillary attraction when the tank is filled or partially filled with liquid. The relation between the louvers 33, the tank 108 and the wicks 111 is such that when the louvers 33 are partially closed, i. e., when the louvers incline downwardly and inwardly from their upper edges and air is drawn through the intake 27 and through the expansion coil 28, the louvers will deflect the air downwardly in and around the various wicks 111 so that if these wicks are wet the air will absorb the moisture therefrom.

Operation

Reference will now be made to the diagrammatic views Figs. 7 to 10, as well as to the other views of the drawings. It is normally desired in fur storage vaults to maintain the temperature of the vault between 60° and 55° F., and accordingly the thermostat 79 may be set so that if the temperature of the vault rises above 60°, the thermostat will close, while the thermostat will open when the temperature in the vault falls below 55°. It will, of course, be appreciated that depending on the desires of the particular vault operator, the thermostat can be set to close when the temperature in the vault rises beyond any desired point and open when the temperature drops beyond any other lower point. The humidostat 78 will also be set so that it will close if the humidity of the air in the vault rises beyond a predetermined point, while the humido-

stat will open when the humidity in the air is decreased slightly below the point for which the closing of the humidostat is set. Generally, the humidostat will be set to close when the relative humidity of the air increases beyond 50% and to open when the relative humidity falls below 45%.

For operating a vault under normal conditions, to maintain the air within the vault at a substantially constant temperature and at a substantially constant humidification, the motor switch for the refrigeration unit 87 will be closed, the main refrigeration switch 81 will be closed, and both the fumigation switch 91 and the ventilation switch 92 will be opened. Assuming that the temperature of the air within the vault is below the point for which the thermostat is set to close and that the humidity of the air in the vault is below the point for which the humidostat 78 is set to close, the louvers 33 will remain open in the horizontal position shown in Fig. 7 and the control damper 59 and fresh air intake damper 72 will be held by the spring 65 to take the position shown in Fig. 7, i. e., the control damper 59 will close off the branch 49b of the housing 49 running to the outside outlet 46 and the branch 49a running to the room outlet 45 will remain open, and the fresh air damper 72 will be closed. Of course, when neither the thermostat 79 nor the humidostat 78 are closed, none of the three motors 53, 37, or 61 will be operated and there will be no circulation of air in the vault within which the unit is located.

Now, let us assume that the temperature of the air in the vault rises beyond the point for which the closing of the thermostat 79 is set but that the relative humidity of the air is still below the requisite relative humidity to close the humidostat 78. The louvers 33, the control damper 59 and the fresh air damper 72 will then be in the position shown in Fig. 7 and an air circulation will be set up as indicated by the arrows in this view. A blower motor circuit will be established from line wire 93 through conductor 94, blower motor 53, conductor 95, fixed contact 81a and movable contact 81c of the main refrigeration switch and conductor 96 to the thermostat 79 and thence through the thermostat, conductor 97, movable contact 81d and fixed contact 81b of the main refrigeration switch and conductor 98 to line wire 93a. Accordingly, the blower motor 53 will be energized and air will be drawn from the plenum chamber A into the blower 48 and ejected outwardly from the blower through the branch 49a of housing 49 and room outlet 45 into the vault or room within which the conditioning unit is located. Air will be drawn into plenum chamber A through the air inlet 27 from the vault and this air as it passes through the expansion coil 28 of the refrigeration unit will be cooled inasmuch as the refrigeration unit will now be in operation. As the louvers 33 are open at this time the air passing through the expansion coil will not be dehumidified because of the fact that a large volume of air is being passed through the coil. In other words, when the louvers 33 are fully open, the air passing through the expansion coil will be in such great volume that the air can be cooled without forming frost on the coil or precipitating water therefrom and, of course, this cooled air will pass directly to the blower to be disseminated into the vault.

If the relative humidity of the air being circulated should rise to a point sufficient to close the humidostat 78, and irrespective of whether or not the thermostat 79 is closed, the louver mo-

tor 37 will be energized to partially close the louvers 33 whereupon the parts will appear as shown in Fig. 8, and the air will be circulated as is there indicated by the arrows. When the louvers are partially closed, the volume of air passing through the expansion coil 28 is materially reduced and this air is intensely cooled, thereby causing the condensation of moisture from the air on the coil 28 in the form of water or frost. Water condensing on the coil 28 may drip into the pan 43 and be carried off therefrom through the pipe 44.

As the humidostat 78 closes, a relay circuit will be established from line wire 93 through conductor 94 and conductor 102 to the coil of the relay 90a and thence through conductor 103 to the humidostat 78 and thence through the humidostat, conductor 104, movable contact 81d of the main refrigeration switch 81 and fixed contact 81b thereof through conductor 98 to line wire 93a. Accordingly, the relay 90a will be energized to attract the armature 90b, thereby causing engagement between the movable contact 90e and the fixed contact 90c and between the movable contact 90f and the fixed contact 90d of the relay switch 90. As the relay switch 90 closes, a blower motor circuit is established from line wire 93 through conductor 94 to the blower motor 53 and thence through the conductor 95, conductor 101, fixed contact 90c, movable contact 90b, conductor 105, and conductor 98 to line wire 93a and, accordingly, the blower 48 if not already in operation will be placed in operation. Similarly, as the relay switch 90 closes, a louver motor circuit will be established from line wire 93 through conductor 94 and conductor 99 to the louver motor 37 and thence through conductor 100, fixed contact 90d, movable contact 90f, conductor 105 and conductor 98 to line wire 93a. The louver motor 37 will thus be energized and this motor will act through the linkage mechanism shown in Fig. 5 to partially close the louvers 33. When the air in the vault has been sufficiently dehumidified for the humidostat 78 to open, and irrespective of whether or not the thermostat 79 is closed, the relay circuit will be broken, thereby causing the relay switch 90 to open, breaking the circuit to the louver motor 37 and breaking the circuit to the blower motor 53 unless the first described blower motor circuit is established through the fact that the thermostat 79 is closed.

It will be seen that when the main refrigeration switch 81 is closed and the refrigeration unit is in operation, the air within the vault will be automatically conditioned both as to temperature and as to humidity so that the air within the vault will be maintained at a certain relatively low temperature level and the relative humidity of the air will be maintained at a certain relatively low level. It is customary in most refrigeration units that controls be provided for automatically defrosting the unit and while such controls are not illustrated, it will be understood that the refrigeration unit may be run through a defrosting cycle from time to time while the main refrigeration switch 81 is closed.

When it is desired to fumigate the vault the main refrigeration switch 81 will be opened and the refrigeration unit switch 87 will be opened. Thereupon the conditioning unit will be allowed to stand idle for perhaps a period of twelve to twenty-four hours without the refrigeration unit in operation and without the blower operating in order that the temperature in the vault may be

raised. When the temperature of the vault is proper the fumigation switch 91 which is located outside the vault will be closed, the ventilation switch 92 being retained in open position, the main refrigeration switch 81 being in open position and the refrigeration unit switch 87 being also maintained in open position. Prior to the closing of the fumigation switch 91 a liquid fumigant of volatile type will be supplied to the tank 108 and the wicks 111 will attract this liquid fumigant by capillary attraction. Now, as the fumigation switch 91 is closed, a relay circuit is established from line wire 93 through conductor 94 and conductor 102 to the winding of the relay 90a and thence through conductor 103 and conductor 106 to the fixed contact 90a of the fumigation switch, thence through the movable contact 90b of the fumigation switch, conductor 101 and conductor 98 to line wire 93a. Accordingly, the armature 90b of the relay switch 90 will be attracted through energization of the relay 90a, thereby bringing movable contact 90c into engagement with movable contact 90e and movable contact 90f into engagement with fixed contact 90d of the relay switch. A blower motor circuit will then be established from line wire 93 through conductor 94 to the blower motor 53 and thence through the conductor 95, conductor 101, fixed contact 90c, movable contact 90e, conductor 105 and conductor 98 to line wire 93a, and the blower will thus be set in operation. Also, a louver motor circuit will be established from line wire 93 through conductor 94 and conductor 98 to the louver motor 37 and thence through conductor 100, fixed contact 90d, movable contact 90f, conductor 105 and conductor 98 to line wire 93a. The louver motor will accordingly be energized and the louvers will be swung to the partially closed position shown in Fig. 9. Air will now be drawn from the vault through the inlet 27 through the inactive expansion coil 28 to be deflected downwardly and inwardly into the plenum chamber A by the partially closed louvers 33 against the wicks 111 carrying the fumigant. The air will absorb the volatile fumigant and will be drawn into the blower 48 and forced out from the blower through the branch 49a of the housing 49 and back into the vault through the room outlet 45. The fumigant accordingly will be circulated to all portions of the vault where it may perform its usual function to kill any insects or bacteriological life within the vault. The conditioning unit as it appears during the fumigation cycle is shown in Fig. 9.

After the vault has been sufficiently fumigated it is necessary to eliminate the fumigant from the vault, and this is done by ventilating the vault. The fumigation switch 91 remaining closed and the main refrigeration switch 81 remaining open and the refrigeration unit switch 87 remaining open, the ventilation switch 92 is now closed. The circuits previously established by closure of the fumigation switch 91 remain established so as to cause operation of the blower motor 53 and the louver motor 37. As the ventilation switch 92 is closed, a damper motor circuit is established running from line wire 93 through conductor 94, conductor 98, a conductor 112 running from the conductor 99 to the damper motor 61, thence through the damper motor 61 and a conductor 113 running from this motor to the fixed contact 92a of the ventilating switch and thence through the movable contact 92b, conductor 107 and conductor 98 to the line wire 75

93a. As the damper motor circuit is established, the damper motor 61 is energized and the control damper 59 and the fresh air inlet damper 72 are moved to the position shown in Fig. 10 and held in this position. In other words, the control damper 59 is swung from a position closing flow through the branch 49b of the discharge casing 49 to a position where the damper 49 closes the branch 49a of the casing. Also, the fresh air damper 72 is swung to open position. The blower 48 now draws air from within the vault through the inlet 27 into the plenum chamber A and forces this air through the outside outlet 46 and conduit 50 to a point outside the vault. As the air within the vault is exhausted therefrom, the pressure within the vault is lowered and, hence, air from outside the vault will be drawn through the conduit 71 into the casing 66 and from the casing through the air filter 70 and the opening 68 into the vault to replace the air exhausted. The unit will be operated in the ventilating condition as shown in Fig. 10 until all the fumigant is expelled from the vault, whereupon on opening the ventilating switch 92 and the fumigation switch 81, all the circuits will be broken to de-energize all three motors 53, 37, and 61, whereupon the louvers 33 will be swung back to full open position and the two dampers 59 and 72 will swing back to the position shown in Figs. 7, 8, and 9. The vault having been cleared of the fumigant, the unit can be again operated on the refrigeration and dehumidification cycle.

It will be seen that a highly efficient conditioning unit for refrigerating, dehumidifying, fumigating and ventilating such rooms as fur storage vaults has been provided. It will be obvious that the device can also be employed for many other uses. Thus, for example, a heating fluid can be supplied to the coil 28 for heating the air if it should be desired to raise the temperature of the air in the room being treated. Also, it is possible to employ the tank 108 and the wicks 111 for humidifying the air to increase the humidity in the air if such is desired.

While it is not essential that the louvers 33 be partially closed during the ventilation cycle of operation, there is some advantage in this to simplify the wiring of the apparatus and to also prevent overload of the blower and to prevent the entrance of air into the vault through the inlet 68 beyond the capacity of the air filter 70 to properly handle the same.

It will, of course, be understood that various changes may be made in the form, details, arrangement and proportions of the various parts without departure from the scope of the present invention which, generally stated, consists in the matter shown, and described, and set forth in the appended claims.

What is claimed is:

1. A refrigeration, dehumidification, and fumigation unit for such rooms as fur storage vaults comprising a casing having a plenum chamber provided with a receiving inlet adapted to receive from the room and a discharge outlet adapted to discharge into the room, a motor operated blower receiving from said plenum chamber and discharging through said outlet, a refrigeration unit having an expansion coil located in said plenum chamber in the path of the air from said inlet to said outlet, a humidifier within which a liquid fumigant may be placed located within said plenum chamber, louvers controlling the flow of air through said expansion coil and located within said plenum chamber in such

relation relative to said humidifier that when the louvers are partially closed the air passing from said inlet to said outlet will be deflected around said humidifier, a thermostatic switch reflecting the temperature in said room and closing when the temperature in the room rises above a particular setting and opening when the temperature lowers below a lower particular setting, a humidostat reflecting the humidity of air within the room and closing when the humidity in the room rises above a particular setting and opening when the humidity in the room lowers beyond a lower particular setting, a louver operating motor, a linkage between said louver operating motor and said louvers for partially closing said louvers when said louver operating motor is energized, means normally urging said louvers to open to full open position when the louver operating motor is not energized, means for controlling the operation of said refrigeration unit, a main refrigeration switch, a first blower motor circuit adapted to be established to said blower motor when said main refrigeration switch is closed as said thermostat closes, a second blower motor circuit adapted to be established when said refrigeration switch is closed upon the closing of said humidostat, a louver operating motor circuit adapted to be established to energize said louver operating motor when said main refrigeration switch is closed and as said humidostat closes, a fumigation switch, a third blower motor circuit adapted to be established to said blower motor when said main refrigeration switch is open and said fumigation switch is closed, and a second louver motor circuit adapted to be established to energize said louver motor when said refrigeration switch is open and said fumigation switch is closed.

2. A refrigeration and dehumidification unit for such rooms as fur storage vaults comprising a casing having a plenum chamber provided with a receiving inlet adapted to receive from the room and a discharge outlet adapted to discharge into the room, a blower receiving from said plenum chamber and discharging through said outlet, a motor for operating said blower, driving means between said blower motor and said blower, a refrigeration unit having an expansion coil located in said plenum chamber in the path of the air from said inlet to said outlet, louvers controlling the flow of air through said expansion coil, a louver operating motor, a linkage between said louver operating motor and said louvers for partially closing said louvers when the louver operating motor is energized, means normally holding said louvers open, a thermostat for reflecting the temperature in the room and adapted to close when the temperature in the room rises above a particular setting and adapted to open when the temperature in the room lowers below a lower particular setting, a humidostat for reflecting the humidity of air within the room and adapted to close when the humidity rises above a particular setting and adapted to open when the humidity lowers below a lower particular setting, a first blower motor circuit adapted to be established through said thermostat when closed to operate said blower motor, a second blower motor circuit adapted to be established as said humidostat closes to operate said blower motor and a louver motor circuit adapted to be established as said humidostat closes to energize said louver operating motor.

3. A conditioning unit for such rooms as fur storage vaults comprising a casing having a

plenum chamber provided with a receiving inlet adapted to receive from the room, a room discharge outlet adapted to discharge into the room and a outside discharge outlet adapted to discharge to a point outside the room, a blower adapted to receive from said plenum chamber and having twin discharge branches, one of which leads to said room discharge outlet and the other of which leads to said outside discharge outlet, a refrigeration unit having an expansion coil located in said plenum chamber in the path of the air from said inlet to said blower, a humidifier located within said plenum chamber and within which a liquid fumigant may be placed, louvers controlling the flow of air through said expansion coil and adapted when partially closed to deflect the air passing to said blower around said humidifier, a conduit for admitting air from a point outside the room to the room, a control damper mounted for alternate positioning to selectively close off one of said two twin branches, a fresh air damper mounted to control flow through said conduit, a blower motor, means for driving said blower from said blower motor, a louver operating motor, a linkage between said louver motor and said louvers for partially closing said louvers when said louver motor is energized, means normally holding said louvers open when said louver motor is not energized, a damper motor, a linkage between said damper motor and said two dampers for opening said fresh air damper and for swinging said control damper to close the branch leading to said room inlet when the damper motor is energized, means normally holding said fresh air damper closed and said control damper positioned to close the branch leading to said outside discharge outlet, a refrigeration unit switch controlling the operation of said refrigeration unit, a main refrigeration switch, a fumigation switch, a ventilation switch, a thermostat reflecting said room temperature and adapted to close when the temperature in the room rises above a certain point and adapted to open when the temperature in the room lowers below a certain lower point, a humidostat switch reflecting the humidity of the air within the room and adapted to close when the humidity in the room rises above a certain point and adapted to open when the humidity in the room lowers below a certain lower point, a first blower motor circuit adapted to be established when said main refrigeration switch is closed and said thermostat is closed, a second blower motor circuit adapted to be established when said main refrigeration switch is closed and said humidostat is closed, a louver motor circuit adapted to be established to energize said louver motor when said main refrigeration switch is closed and said humidostat is closed, a third blower motor circuit adapted to be established when said main refrigeration switch is open and said fumigation switch is closed, a second louver motor circuit adapted to be established to energize said louver motor when said main refrigeration switch is open and said fumigation switch is closed, and a damper motor circuit adapted to be established to energize said damper motor when said main refrigeration switch is open and said ventilation switch is closed.

4. A refrigeration, dehumidification, fumigation and ventilation unit for such rooms as fur storage vaults, comprising a casing provided with a plenum chamber having a room receiving inlet, a room discharge outlet and an outside discharge outlet adapted to be connected to dis-

charge outside the room; a fresh air conduit section carried by said casing, having a receiving portion adapted to be connected with a source of air supply located outside the room and having a discharge portion for discharging into the room; damper means controlling said two outlets and said fresh air conduit section and normally urged to a first position closing said outside discharge outlet, opening said room discharge outlet and closing said fresh air conduit section, but capable of being moved to a second position opening said outside discharge outlet, closing said room discharge outlet, and opening said fresh air conduit section; a blower mounted in said casing to receive from said plenum chamber and discharge through which ever of said outlets is open; a refrigeration unit having an expansion coil located within said plenum chamber and through which the air must pass in its travel from said room receiving inlet through said plenum chamber to said blower and through which ever discharge outlet is open; a humidifier located within said plenum chamber and within which a liquid fumigant may be placed; thermostatically controlled means for operating said blower in association with the expansion coil of said refrigeration unit to maintain the temperature of the room within a certain low temperature range when said damper means is in its first position and the humidity in the room is below a certain low humidity range; humidostatically controlled means for operating said blower in association with the expansion coil of said refrigeration unit to maintain the humidity of the room within the said low humidity range irrespective of the temperature of the room; a control device which can be operated to throw both said thermostatically controlled means and said humidostatically controlled means out of operation; independent means for operating said blower when said damper means is in the first position, said control device is operated and a liquid fumigant is placed within said humidifier to fumigate the chamber; and other independent means for simultaneously operating said blower, moving said damper means to its second position and for maintaining said damper means in its second position to ventilate the room when said control device is operated.

5. A refrigeration, dehumidification fumigation and ventilation unit for such rooms as fur storage vaults comprising a casing provided with a plenum chamber having a room receiving inlet, a room discharge outlet, and an outside discharge outlet adapted to be connected to discharge outside the room; a fresh air conduit section, carried by said casing, having a receiving portion adapted to be connected with a source of air supply located outside the room and having a discharge portion for discharging into the room; damper means controlling said two outlets and said fresh air conduit section and normally urged to a first position closing said outside discharge outlet, opening said room discharge outlet, and closing said fresh air conduit section, but capable of being moved to a second position opening

said outside discharge outlet, closing said room discharge outlet and opening said fresh air conduit section; damper operating means adapted when energized to move said damper means from its first position to its second position and to hold said damper means in its second position; a blower mounted in said casing to receive from said plenum chamber and discharge through which ever of said outlets is open; a refrigeration unit having an expansion coil located within said plenum chamber and through which the air must pass in its travel from said room receiving inlet through said plenum chamber to said blower and through which ever discharge outlet is open; means controlling the cooling effect of said expansion coil relative to the air passing there through to in a first setting cool air passing there through to a certain temperature and to in a second setting cool air passing there through to 20 a certain temperature well below said first mentioned temperature; a thermostat mounted to reflect the room temperature and adapted to close when the temperature in the room rises above a certain range, and adapted to open when the temperature in the room lowers below that certain range; a humidostat reflecting the humidity of the air within the room and adapted to close when the humidity in the room rises above a certain range and adapted to open when the humidity in the room lowers below that certain range; a main switch; a circuit adapted to be established through said main switch and said thermostat when closed to set said controlling means in its first setting and operate said blower 30 motor, to cool the air in the room when the humidity of the air in the room is below the range for which said humidostat is set; a circuit adapted to be established through said main switch and said humidostat when closed to set said controlling means in its second setting and operate said blower motor when the humidity in the room rises above the range for which the humidostat is set, to control the humidity in the room; a switch controlled circuit adapted to be established to said blower motor when said main switch is open and a liquid fumigant is placed within said humidifier, to circulate fumigant through the room; and a switch controlled circuit adapted to be established to said blower motor and to said damper operating means to energize the same, to ventilate the room.
